SUPPORTING RACK

Roy S. Risdon, San Francisco, Calif.

Application June 1, 1937, Serial No. 145,682

6 Claims. (Cl. 211—181)

The present invention relates generally to a display rack or support for garments and like articles, and more particularly to an improved construction for supports of this character in which a minimum number of parts are required, which parts are adapted to be assembled together in a simple and convenient manner, without resort to additional securing means.

An object of the invention is to provide a novel construction for a display rack or support for garments and the like, that can be made of solid or tubular material and which can be quickly assembled and disassembled in a simple and convenient manner.

Another object of the invention is to provide a simple form of display rack or support which can be constructed either in miniature, as a toy for children, or as a full size device for adult use. A further object of the invention is to provide in a supporting rack a novel arrangement of interlocking parts which, when assembled, will form a rigid support without resort to bracing and/or other securing means.

For a better understanding of the invention reference should be had to the accompanying drawing, wherein there is shown by way of illustration and not of limitation, preferred embodiments thereof.

In the drawing:

Figure 1 is a perspective view of a garment hanger supporting rack constructed in accordance with this invention.

Figures 2 and 3 are enlarged fragmentary views showing details of the support of Figure 1.

Figure 4 is a modified form of the support shown in Figure 1, having additional and swingable supporting arms thereupon.

Figure 5 is a further modification of the support shown in Figure 1, having additional and parallel supporting arms, and

Figure 6 is a detail of the support shown in Figure 5.

As illustrated in Figure 1, my improved support, in its preferred form, comprises end frames 10 and 11, which provide respectively the right and left hand ends of the support. These end frames 10 and 11 are similar in appearance, except, as will hereinafter appear, details thereof are formed thereupon so as to provide right and left hand cooperating parts. The end frame 10 has a horizontally disposed loop 12 at its lower end, which is adapted to form a floor engaging portion, and the end frame 11 has a similar horizontally disposed loop 13, which likewise forms a floor engaging portion. Along the top and near sides of

the loops 12 and 13 there is respectively provided a pair of horizontally spaced loops 14 and 15, and at the upper ends of the end arms 10 and 11 there is also respectively provided vertically spaced loops 16 and 17. Extending between the end frames 10 and 11 there is a bottom spacing stay rod 18 having right angled ends 19 and 20, which are respectively inserted through the loops 14 and 15 upon the end frames 10 and 11, and extending between the upper ends of the end frames 10 and 11 there is a top spacing stay rod 21 having right angled ends 22 and 23, which are respectively passed through the loops 16 and 17 at the upper ends of the end frames 10 and 11.

With this arrangement it will be seen that the horizontally disposed ends 19 and 20 of the bottom spacing stay rod 18 serve to hold the floor engaging portions 12 and 13 of the end frames in parallel relation, and that the vertically disposed ends 22 and 23 of the top spacing stay rod 21 will serve to maintain the end frames 10 and 11 in their vertical positions, so that should the rack be intended as a garment support, garment hangers 24 may hang therefrom. The arrangement here shown will be particularly useful in stores for displaying dresses and the like, as during sales, where a large number of dresses are usually on display, the advantage being that when the racks are not required, they may be easily disassembled and stored away in a compact manner. In a rack of this character, it is contemplated that the end frames and the spacing stay rods may be formed of tubular material, whereas, should the device be intended as a toy for the hanging of doll's clothes and the like, the parts may be made of solid material, such as heavy wire. In either event it will be appreciated that the principle of assembling and the arrangement of parts will be identical in both the full size and the miniature devices.

As shown in Figure 2, the upper loops 16 and 17 upon the end frames 10 and 11 project inwardly upon the end frames so that the ends 22 and 23 of the top spacing stay 21 can be easily inserted therein.

Upon referring to Figure 3 of the drawing, it will be noted that the end frames 10 and 11 are formed of a single piece of rod or tubing, and that the loops 14 and 15 are formed in spaced relation at the extreme end of the wire or tube, with one of the loops 14 and 15 located substantially centrally of the floor engaging loops 12 and 13 upon the end frames. With this arrangement of loops it will be seen that the bottom spacing stay rod 18 will be located immediately below and

in line with the top spacing stay rod 21. In connection with this detail of the present invention it will be understood that the horizontal loops 14 and 15 may be provided at either side 5 of the center of the loops 12 and 13, or they may be formed in the bottom portion of these loops.

The embodiment of the invention illustrated in Figure 4 of the drawing, comprises, in addition to the above described parts, the provision 10 of additional loops 25 and 26 intermediate the ends of the end frames 10 and 11, into which swingable rods 27 having right angled ends 28 are adapted to be supported. With this arrangement the swingable rods 27 may be located in any 15 convenient position to provide supports for additional garments or other articles.

In the embodiment illustrated in Figure 5, the end frames and the top and bottom spacing stays are similar to those above described, and 20 like the embodiment illustrated in Figure 4, the end frames 10 and 11 of this embodiment have spaced loops 25 between their ends into which a downwardly depending end 29 upon cross arms 30 are adapted to be inserted. When the cross 25 arms 30 are used upon the end frames 10 and 11, as shown in this figure of the drawing, they will serve as a support for additional garment supporting rods 31, which will be located below and at opposite sides of the top spacing stay rod 21.

30 As shown in Figure 6 of the drawing, the cross arms 30 have horizontally disposed loops 32 at the ends thereof for the ends of the rods 31, and the middle of these cross arms are folded so as to form the downwardly depending ends 29 intermediate the ends thereof.

With the arrangements above described, it will be understood that by properly proportioning the vertical height of the end frames 10 and 11 and the length of the spacing stay rods 18 and 40 21, the device may be adapted to many uses. For example, with the last above described embodiment it is conceivable that with the end frames 10 and 11 having a height of approximately four feet (4'), the device will provide a 45 convenient and practical towel rack, such as is used in bathrooms and the like.

While I have, for the sake of clearness and in order to disclose my invention so that the same can be readily understood, described and illustrated specific devices and arrangements, I desire to have it understood that this invention is not limited to the specific means disclosed, but may be embodied in other ways that will suggest themselves to persons skilled in the art. It is 55 believed that this invention is new and it is desired to claim it so that all such changes as come within the scope of the appended claims are to be considered as part of this invention.

Having thus described my invention, what I 60 claim and desire to secure by Letters Patent is:—

1. In a display rack or garment supporting holder of the character described constructed entirely of solid or tubular material, comprising end frames having transversely bent floor engaging portions with two horizontally spaced loops formed therein for the reception of the ends of a spacing stay rod, a vertically extending portion upon said end pieces having vertically spaced loops at the top for the reception of the ends of 65 a second spacing stay rod, and a pair of similar spacing stay rods having their ends bent at a right angle and inserted into the spaced loops at the top and bottom of said end frames, whereby said end frames will be held in a vertical position 70 and hold the upper spacing stay rod in a posi-

tion to be used as a support for articles to be displayed.

2. In a rack or holder of the character described constructed entirely of solid or tubular rods, comprising end frames having transversely bent floor engaging portions with horizontally spaced loops formed therein for the reception of the ends of a bottom spacing stay rod, a vertically extending portion upon said end frames having vertically spaced loops formed therein at the top 10 for the reception of the ends of a top spacing stay rod, and a top and bottom spacing stay rod having their ends bent in the same direction at a right angle and inserted respectively into the horizontally and vertically spaced loops at the 15 top and bottom of said end frames, the bent end portions of said top and bottom stay rods when inserted in the horizontally and vertically disposed loops of the end frame serving to hold said end frames upright and parallel. 20

3. In a rack of the character described constructed entirely of solid or tubular rods, comprising end frames having flattened horizontally disposed loops forming floor engaging portions with horizontally spaced loops formed along the 25 upper side of said loops for the reception of the ends of a bottom spacing stay rod, a vertical portion extending upwardly from the horizontal loops of said end frames having vertically spaced loops at the top thereof for the reception of the 30 ends of a top spacing stay rod, and a top and bottom spacing stay rod having their ends bent at a right angle and inserted respectively into the horizontally and vertically spaced loops at the top and bottom of said end frames. 35

4. In a rack of the character described constructed entirely of solid or tubular rods, comprising end frames having transversely bent floor engaging portions with horizontally spaced loops formed therein for the reception of the ends of a 40 bottom spacing stay rod, a vertically extending portion upon said end frames having vertically spaced loops at the top for the reception of the ends of a top spacing stay rod, a top and bottom spacing stay rod having their ends bent at a right 45 angle and inserted respectively into the horizontally and vertically spaced loops at the top and bottom of said end frames to hold said end frame in vertically spaced relation, the vertically extending portions of said end frames each having, 50 a pair of additional spaced loops intermediate its ends, and a supporting arm removably carried by the additional spaced loops upon said end frames.

5. In a display rack of the character described, 55 constructed entirely of solid or tubular material, comprising end frames having transversely bent floor engaging portions with two horizontally disposed loops formed therein for the reception of the ends of a bottom spacing stay rod, a vertically extending portion upon said end pieces having vertically spaced loops for the reception of the ends of a top spacing stay rod, a pair of spacing stay rods having their ends bent at a right angle and inserted into the spaced loops at 65 the top and bottom of said end frames, whereby said end frames will be held upright and in spaced relation, and display supporting rods removably supported upon said end frames between said spacing stay rods. 70

6. In a rack of the character described constructed entirely of solid or tubular rods, comprising end frames having transversely bent floor engaging portions with horizontally spaced loops formed therein for the reception of the ends of 75

a bottom spacing stay rod, a vertically extending portion upon said end frames having vertically spaced loops at the top for the reception of the ends of a top spacing stay rod, a top and bottom 5 spacing stay rod having their ends bent at a right angle and inserted respectively into the horizontally and vertically spaced loops at the top and bottom of said end frames to hold said end frame in vertically spaced relation, the vertically ex-

tending portions of said end frames each having a pair of additional spaced loops intermediate its ends, a transversely disposed arm removably carried by the additional spaced loops upon each of said end frames, and an article supporting rod 5 extending between the ends of said transversely disposed arms.

ROY S. RISDON.
